UNITED STATES PATENT OFFICE

130,746

DESIGN FOR A CHILDREN'S SAND BOX OR SIMILAR ARTICLE

Carl H. Oermann, York, Pa.

Application September 22, 1941, Serial No. 103,444

Term of patent 7 years

To all whom it may concern:

Be it known that I, Carl H. Oermann, a citizen of the United States of America, residing at York, in the county of York and State of Pennsylvania, have invented a new, original, and ornamental Design for a Children's Sand Box or Similar Article, of which the following is a specification, reference being had to the accompanying drawing, forming part thereof, wherein

Fig. 1 is a perspective view of a children's sand box or similar article embodying my new design, the top being shown in lowered position; and

Fig. 2 is a perspective view thereof, showing the top in raised position.

I claim:

The ornamental design for a children's sand box or similar article, as shown.

CARL H. OERMANN.
